DESIGN FOR A MOTOR COACH BODY

Everett W. Allen, Birmingham, Mich., assignor to Yellow Truck & Coach Manufacturing Company,
Pontiac, Mich., a corporation of Maine

Application October 2, 1939, Serial No. 87,469

Term of patent 7 years

To all whom it may concern:

Be it known that I, Everett W. Allen, a citizen of the United States and a resident of Birmingham, county of Oakland, State of Michigan, have invented a new, original, and ornamental Design for a Motor Coach Body, of which the following is a specification, reference being made to the accompanying drawing, forming a part thereof.

In the drawing:

Fig. 1 is a side perspective view of a motor coach body, showing my new design;

Fig. 2 is an elevational view showing the side opposite that illustrated in Fig. 1;

Fig. 3 is a top plan view;

Fig. 4 is a front elevational view, and

Fig. 5 is a rear elevational view thereof.

I claim:

The ornamental design for a motor coach body, as shown.

EVERETT W. ALLEN.
